AMBIENT TEMPERATURE COMPENSATING MEANS FOR AUTOMATIC CIRCUIT BREAKERS

Ernst Besag and Walter Edward Hill, Streetly, and Thomas Daniel Guy Wintle, Walsall, England, assignors to J. A. Crabtree & Co. Limited, Walsall, Staffordshire, England, a British company

Application August 12, 1948, Serial No. 43,824
In Great Britain August 14, 1947

7 Claims. (Cl. 297—15)

1

This invention relates to improvements in the trip mechanism of automatic circuit breakers and similar electrical switchgear, and is particularly concerned with mechanism, operated by thermal release overload devices, and which provides ambient temperature compensation, for use with motor protective switches.

According to this invention, a rotationally adjustable member is formed with a cam adapted for adjusting the ambient temperature compensating means which is engageable by the trip mechanism upon the occurrence of overload conditions. Such ambient temperature compensating means may be in the form of a bimetallic blade adapted to be rocked in see-saw fashion upon the stem of an adjusting screw, so that the gap between the blade and the trip mechanism may be varied.

In order to enable the invention to be readily understood, reference will now be made to the accompanying drawings illustrating, by way of example, one construction for carrying the invention into effect, in which drawings:

Figure 1 is a perspective view of a casing for the ambient temperature compensating means of our present invention, showing the same mounted on the end of an overload box.

Figure 2 is a plan view of the device shown in Figure 1, the cover of the casing having been removed to disclose the interior mechanism.

Figures 3 and 4 are sectional views on the lines III—III and IV—IV, respectively, of Figure 2, with the cover mounted in position.

Figure 5 is a sectional view on the line V—V of Figure 3.

Figure 6 is a sectional view on the line VI—VI of Figure 4.

Referring to the drawings, a cap or sleeve *a* is rotationally adjustable on a boss *b* upstanding from an insulating box casing *c* secured to a back plate *l* by bolts *2*, which casing houses thermal overload release devices (not shown), which devices are operative to actuate a trip bar *m*. For a more complete understanding of the construction and operation of the present invention, reference is made to our Patents 2,523,897 of September 26, 1950, relating to "Thermal Overload Release Device for Automatic Circuit Breakers," and 2,527,907 of October 31, 1950, relating to "Automatic Circuit Breaker Having Thermal Overload Release Units," in which patents there is an adequate disclosure of thermal overload release devices, particularly trip bars and their associated mechanisms corresponding to the trip bar *m* of the present invention. The

cap *a* is formed on its upper surface with a cam *d* engageable by one end of a bimetallic blade *e* which serves as a means for compensating for ambient temperature, and around said cap is arranged a part cylindrical metal clip or sleeve *f* having graduations or markings thereon which co-operate with a fixed pointer *g* on the cover *h* of the casing *c* for indicating the setting of the device.

10 Inside the cap *a*, a bow-shaped blade spring *i* is provided, which spring is disposed parallel to the axis of the boss *b* in a narrow slot *k* in the latter. For the purpose of locating the spring *i*, its inwardly extending ends are engaged in recesses *k*¹ in the ends of the boss *b*. The spring *i* acts for taking up tolerances between the cap *a* and its bearing on boss *b*, and for frictionally retaining the cam *d* in any desired position.

A small outwardly-projecting stop *c*¹ on the boss *b*, has abutting engagement with a complementary inwardly-projecting lug *a*¹ on the cap *a* for the purpose of limiting rotational adjustment of the latter in either direction of rotation.

The end of the bimetallic blade *e* remote from the cam, is adjustable in relation to the trip bar *m*, and for this purpose, said blade is acted upon between its ends by any suitable adjusting means. According to one example, a screw *n*, seated by spring pressure in a semi-cylindrical threaded groove *o* in the casing *c*, is operated so that a shoulder *n*¹ thereon is pressed against the face of the blade *e* so that the gap *x* between the end of said blade and the end of trip bar *m* may be varied.

35 For imparting guidance to screw *n*, a reduced stem *n*² on said screw may extend freely through an opening in the blade *e* and into an opening *c*² in the casing *c*. The screw *n*, which may be held in the threaded groove *o* of the casing *c* by a spring blade *p* of right-angled shape, extends 40 through an opening in the longer arm *p*¹ of said spring blade the other spring arm *p*² of said spring blade being engaged beneath a shoulder *c*³ of the casing *c* for stressing said spring. The downward thrust exerted by the spring blade *p* on the screw *n* not only serves to keep said screw seated in the semi-cylindrical threaded groove *o*, but also serves to maintain said screw in its various positions of adjustment. The kerfed, outer 45 end of screw *n* is accessible through an opening *h*¹ in the cover *h*, this opening being closed by a spring clip *r* when adjustment has been effected. The clip *r*, which prevents unauthorized access to the adjusting screw *n*, is bent to extend over 50 the opening *h* in the end of the casing, one end

of said clip being engageable in a groove *s* in the bottom of the casing *c*, and the other end having a small circular opening which is pressed over a stud *t* on the top of the cover *h* for retaining the latter in place.

After initial adjustment of the bimetallic blade *e* has been effected in the factory by turning the screw *n*, subsequent adjustment may be made by rotating the knurled cap *a* and cam *d* so as to rock the blade *e* upon the stem *n* for variation of the gap *x*.

Having thus described our invention, we claim:

1. An ambient temperature compensating means for automatic circuit breakers of the thermal overload release type which include trip mechanism and a trip bar for actuating said mechanism, said compensating means comprising an elongated bimetallic blade; a casing enclosing said ambient temperature compensating means, said casing having an opening through a wall thereof and having a threaded, substantially semi-cylindrical groove on a portion thereof in alignment with said opening; a screw in threaded engagement with said groove and passing transversely through an opening in the intermediate portion of said blade; means operatively engaging said screw to retain said screw in engagement with said groove, said screw constituting a pivotal mounting for said blade and having a shoulder thereon engageable with said blade whereby rotation of said screw will move said blade laterally to vary the position of its pivotal mounting, one end of said blade being normally spaced from an end of the trip bar of the circuit breaker but engageable by said end of said trip bar upon the occurrence of overload conditions; and adjusting means engaging the other end of said blade to rock the same about said screw to vary the spacing between the first-mentioned end of said blade and said one end of said trip bar independently of the position of the pivotal mounting of said blade.

2. An ambient temperature compensating means as defined in claim 1 in which the casing is provided with a second opening in axial alignment with the first-mentioned opening, and in which an end of said screw enters said second opening whereby said screw is guided in its axial movements.

3. An ambient temperature compensating means as defined in claim 1 in which the casing is provided with a second opening of lesser diameter than that of said first-mentioned opening and in axial alignment therewith, and in which said screw has a reduced terminal portion which enters said second opening whereby said screw is guided in its axial movements.

4. An ambient temperature compensating means for automatic circuit breakers of the thermal overload release type which include trip mechanism and a trip bar for actuating such mechanism, said compensating means comprising an elongated, bimetallic blade; a casing enclosing said ambient temperature compensating means, said casing having an opening through a wall thereof and having a threaded, semi-cylindrical groove on a portion thereof in align-

ment with said opening; a screw in threaded engagement with said groove and passing transversely through an opening in the intermediate portion of said blade, said screw constituting a pivotal mounting for said blade and having a shoulder thereon engageable with said blade whereby rotation of said screw will move said blade laterally to vary the position of its pivotal mounting, one end of said blade being normally spaced from an end of the trip bar of the circuit breaker but engageable by said end of said trip bar upon the occurrence of overload conditions; adjusting means engaging the other end of said blade to rock the same about said screw to vary the spacing between said first-mentioned end of said blade and said end of said trip bar independently of the position of the pivotal mounting of said blade; and an L-shaped spring having an aperture in one arm thereof through which said screw passes and the other arm of which resiliently engages said casing to keep said screw in contact with the semi-cylindrical threaded groove in said casing.

5. An ambient temperature compensating means for automatic circuit breakers of the thermal overload release type which includes trip mechanism and a trip bar for actuating such mechanism, said compensating means comprising an elongated, bimetallic blade pivotally mounted intermediate its ends, one end of said blade being normally spaced from an end of the trip bar of the circuit breaker but engageable by said end of said trip bar upon the occurrence of overload conditions; a casing enclosing said ambient temperature compensating means; a boss projecting inwardly of said casing; a cap rotatably mounted on said boss; and a cam on said cap and rotatable therewith, said cam engaging the other end of said blade to rock the blade about its pivotal mounting to vary the spacing between the first-mentioned end of said blade and said end of said trip bar.

6. An ambient temperature compensating means as defined in claim 5, in which a pointer is positioned on the casing, and in which the cap is provided with markings, cooperation between said pointer and markings indicating the position of said cam.

7. An ambient temperature compensating means as defined in claim 5 in which a bow-shaped spring is disposed parallel to the axis of the boss in a narrow slot in said boss and has its intermediate bowed portion frictionally engaging the interior of said cap.
